UNITED STATES PATENT OFFICE.

ELMER R. POPE, OF HAMILTON, MASSACHUSETTS, ASSIGNOR TO UNITED SHOE MACHINERY CORPORATION, OF PATERSON, NEW JERSEY, A CORPORATION OF NEW JERSEY.

NAILING MACHINE.

Application filed November 27, 1922. Serial No. 603,576.

This invention relates to nailing machines, it being of particular utility in connection with apparatus for nailing the heel-seats of shoes. In work of this character, the location of the nails securing the heel-seat elements together is of much importance. They should be well out toward the rand-crease to maintain this as tight as possible, yet must not be so far in this direction as to 10 be beyond the edge of the insole. The nailing design, or the points of insertion of the fasteners, in previous machines has been changed for groups of sizes of shoes, employing in this connection a multiple die-block in which each design, or nail-arrangement, serves for a plurality of sizes. But this is unsatisfactory, since the variation of the sizes within each group gives only an 15 approximation of the correct nail-positions. It is an object of the present invention to provide for a location of the points of insertion of the fasteners best suited to each size of shoe to be nailed, this being determined by the contour of the work itself in proximity to the rand-crease. For this purpose, 20 I employ a sectional die-block, as one having slots in which nail-holding members are movable. The drivers by which the insertion of the nails is effected are also preferably movable to correspond to variations 25 in the die-block, this being brought about by surfaces upon the nail-holding members, with which surfaces the drivers contact. I have shown this movement of the drivers as 30 permitted by their mounting upon carriers sliding in ways in the driver-plate.

In the accompanying drawing,

Fig. 1 shows a transverse vertical section through the driver-assembly and die-block 40 of a heel-seat-nailing machine embodying my invention in one of the several forms it may assume, while

Fig. 2 is a top plan view of these elements, parts being broken away.

In the frame 10 of the apparatus, which 45 may be organized generally as is the well-known Lightning heel-attaching machine, is supported a horizontal die-block 12 resting in ways 14 in the frame. Mounted upon the frame to reciprocate toward and from the die-block is a plate 16, upon which are arranged drivers 18. Both the die-block and driver-assembly are of sectional construction, these sections of the respective parts

together furnishing nail-inserting mechanisms, which will now be described in detail.

The body 20 of the die-block has, at each side of its minor axis, a series of slots 22, these diverging outwardly. The lower portions of the slots extend at 24 farther from 55 the center of the block than the upper portions. The block also includes a plate 26 secured by screws upon the under side of the body 20. In this plate is a central, imperforate portion 28 acting as an abutment 60 for the heel-seat of a jacked shoe which is pressed against it. It is shown as serrated upon its contact-surface to prevent accidental displacement of the work. At each side of the imperforate portion 28 are openings 70 30, 30, and beyond these are other openings 32, 32, there being, between the openings 30 and 32, bars 33, which may be integral with the plate. Arranged to slide in the slots 22, 24 and in the openings 32 are nail-holding 75 members 34, the bodies of which are situated within the slots 24, while upward projections 36 rise through the slots 22, and downward projections 38 extend below the plate 26 through the openings 32. In the projection 80 36 of each nail-holding member is a slot 40 having parallel side walls and end walls 42, 44 converging to openings 46, in which nails N may be temporarily held for driving. The openings 46 are shown as somewhat inclined inwardly and downwardly, so that they are substantially perpendicular to tangents to the curvature of an outsole at the entering points of the nails. For the retention 85 of the nails within the openings, plungers 48 are provided, movable within bores within the body-portions of the nail-holding members and having their ends urged into the nail-holding openings by springs 52 interposed between them and screws closing 90 the outer extremities of the bores. The nail-holding members are yieldably maintained 90 in their inward positions, at least so closely together that the heel-seat nails for the smallest size of shoes to be operated upon 100 will be correctly placed, by springs 54 carried in bores in the die-block 20 and backed by screws at the outer ends of the bores.

When a jacked shoe S is carried into the nailing position, its counter-portion, at opposite sides just below the rand-crease, contacts with rolls 56, each of which rolls is rotatably mounted upon an arm 58 secured

upon the lower face of the projection 38 from one of the nail-holding sections. These arms, with their rolls, are preferably adjustable toward and from the work and transversely thereof by screw-and-slot connections 60. By this means, such a relation is established between the rolls and the work and between the nail-holding openings 46 and said work, that the openings vary in position in accordance with the contour of the counter-portion of the shoe, and will be best situated with respect to the rand-crease. It will be observed that there are included in the body 20 of the die-block, nail-holding openings 62, 62, coming at the rear of the heel-seat and which are not variable in position. This is due to the fact that, for all sizes of shoes, the relation to these openings is unchanged.

10 The drivers 18 are respectively fixed in carriers 64 independently movable in horizontal ways 66 in the driver-plate 16, these carriers and their supports being vertically alined with the slots 22 and 24, so that in 15 their inward and outward movement the drivers and nail-holding openings 46 may be made to coincide. The carriers are normally forced inwardly, to positions in which the drivers are situated vertically over the 20 openings 46 when the nail-holding sections 34 are at their most inward positions, by springs 68 held in horizontal bores in the driver-plate and backed by end-plates 70 screwed to the outer edges of such driver-plate.

In using the apparatus, the rolls 56 are adjusted upon the nail-holder projections 38 until, for the particular style of shoe which is to be operated upon, movement of the 25 sections 34 by contact of the rolls with the work will locate the nail-holding openings 46 as near the rand-crease as possible and still keep the inserted fastener within the insole. Since the contact of the rolls is directly with the shoe-upper, and since they 30 may be placed close to the rand-crease, great accuracy of location for the nails may be attained. The loading mechanism of the machine drops the nails into the slots 40, 35 they being directed by the inclined surfaces 42 and 44 into the openings 46, where they are held by the plungers 48. When the operator moves in the jacked shoe S to nailing 40 position, the contact of its counter-portion with the rolls 56 separates the sections 34 until the openings 46 are correctly related to the heel-seat. Upon the descent of the drivers 18, these either directly enter the 45 openings 46 to drive the nails N into the heel-seat, or their ends contact with the surfaces 44. These exert upon the drivers forces having components acting longitudinally of the ways 66, and causing the carriers 64 to be moved outwardly against their 50 springs until the drivers are alined with the

openings, so that the engagement with and driving of the nails may take place. To the inclination of the openings 46 the drivers may adapt themselves by their own resiliency. It will be seen that without the removal and replacement of the parts, each size of shoe to be nailed has, by my improved machine, the fasteners inserted at the most advantageous points.

Having described my invention, what I claim as new and desire to secure by Letters Patent of the United States is:

1. In a heel-seat-nailing machine, a plurality of nail-inserting mechanisms including independently movable sections, the sections having position-determining projections contacting adjacent to the rand-crease with the counter-portion of a shoe to be nailed and arranged to determine the relation of the points of insertion of the nails in the outsole to said rand-crease.

2. In a shoe-nailing machine, a plurality of nail-inserting mechanisms including independently movable sections, the sections having portions contacting with a shoe to be nailed to determine the points of insertion of the nails, and means arranged to adjust the contact-portions independently upon their sections transversely of the shoe.

3. In a heel-seat-nailing machine, a plurality of nail-inserting mechanisms including independently movable sections, the sections having position-determining projections, rolls mounted upon the projections and arranged to contact adjacent to the rand-crease with the counter-portion of the shoe to be nailed during the movement of said shoe to nailing position, and springs acting upon the sections and arranged to force the rolls into contact with the work.

4. In a shoe-nailing machine, the combination with reciprocatory drivers, of a die-block arranged to act as an abutment for the work and provided with slots, and nail-holding members yieldably mounted in the slots.

5. In a shoe-nailing machine, the combination with reciprocatory drivers, of a die-block arranged to act as an abutment for the work and provided with slots, and nail-holding members movable in the slots and having portions depending below the die-block for contact with the shoe to be nailed.

6. In a shoe-nailing machine, the combination with reciprocatory drivers, of a die-block provided with slots, and nail-holding members yieldably mounted in the slots and each having a body-portion in which the nails are held for driving and an upwardly extending nail-receiving portion.

7. In a shoe-nailing machine, a plurality of nail-inserting mechanisms including independently movable sections provided with nail-receiving passages and intersecting passages, and a nail-retaining member movable

- in the intersecting passage of each section.
8. In a nailing machine, a die-block having an imperforate portion for contact with the work and openings at opposite sides of the imperforate portion, and nail-holding sections yieldably mounted to move over the openings.
9. In a nailing machine, a die-block having an imperforate portion for contact with the work and openings at opposite sides of the imperforate portion, and nail-holding sections movable over the imperforate portion and extending through the openings.
10. In a nailing machine, a die-block having an imperforate portion for contact with the work and openings at opposite sides of the imperforate portion, and nail-holding sections extending through the openings into contact with the work.
11. In a shoe-nailing machine, nail-holding members variable in position in accordance with a shoe to be nailed, and drivers movable independently of one another, said drivers and holding members being relatively movable into and out of co-operation, the holding members having surfaces for contact with the drivers to position said drivers in accordance with the variation in the holding members.
12. In a nailing machine, movable die-block-sections provided with nail-holding openings and with positioning surfaces, and drivers movable into and out of co-operation with the openings and being movable independently of one another by contact with the positioning surfaces.

13. In a shoe-nailing machine, a plurality of nail-inserting mechanisms including independently movable sections, the sections having portions contacting with a shoe to be nailed to determine the points of insertion of the nails, and drivers mounted independently of the sections and being movable by contact therewith.

14. In a nailing machine, a driver-plate provided with ways, a carrier mounted to move in the ways, a driver fixed against movement upon the carrier, and nail-holding means arranged to move the carrier.

15. In a nailing machine, a driver-plate provided with ways, a carrier mounted to move in the ways, a driver fixed to the carrier, and a die-block having an inclined surface with which the driver contacts to move the carrier.

16. In a nailing machine, a driver-plate provided with ways, oppositely movable carriers mounted in the ways, springs for forcing the carriers toward each other, and nail-holding means arranged to separate the carriers.

17. In a nailing machine, a driver-plate provided with ways, carriers mounted to move in the ways independently of one another, springs arranged to maintain the carriers normally at one extreme of their path of movement, and a driver fixed to each carrier.

In testimony whereof I have signed my name to this specification.

ELMER R. POPE.
